ABSTRACT: A removable core for forming an axial opening in concrete beams includes an elongated hollow tubular core member or body formed of elastomeric material, together with end caps for sealing the ends of the body and means for pressurizing the interior of the body during the concrete casting process. The body in cross section includes a square outer periphery so that the amount of concrete required to form a beam is reduced. The body maintains its square shape when pressurized without the use of reinforcing or supporting structure. In one arrangement, the walls of the body are of substantially equal thickness throughout and are bowed inwardly at the sides of the square. In another arrangement, the inner wall of the body is circular so that upon pressurization there is no tendency for the square outer shape to be distorted.

CORES FOR CASTING CONCRETE BEAMS

The present invention relates to cores for use in casting hollow concrete members such as beams, slabs and the like.

In the manufacture of prestressed concrete beams, one widely used procedure is to cast a concrete beam having a central longitudinal opening extending the length of the beam. After the concrete has set, tendons such as cables, wires or rods passing through the beam are tensioned thereby to subject the beam to compressive stress. In the past, hollow beams have been formed by using cores which are expanded or pressurized while the concrete is setting and which are contracted or depressurized and removed from the beam thereafter.

A known type of core includes an elongated, circular cylindrical tube having a wall formed of a flexible material such as rubber. The tube is placed within a mold for the beam and the tube is enveloped with concrete when the mold is filled. The tube is pressurized while the concrete sets so that it maintains its shape and does not collapse under the weight of the concrete. When the concrete is strong enough to retain its shape without internal support the tube is deflated and removed from the beam. This type of core has the important advantages of simplicity and low cost.

It has also been proposed to use a core having a polygonal rather than a round outer shape. A square configuration, for example, provides a saving in material cost by reducing the amount of concrete used in the beam, and does not substantially reduce the strength of the finished beam. In the past it has not been possible to use a simple square tube formed of rubber or the like and constructed along the lines of the round tubes used in the past because when pressurized such a square tube is forced into a rounded shape. Because of this difficulty, square cores developed to date have been subject to the disadvantages of complexity and high cost due to the inclusion of structure required to support or reinforce the core in order to assure that the square shape is maintained when the core is pressurized.

Accordingly, one object of the present invention is to provide an improved core for use in casting hollow concrete beams.

Another object is to provide improved core members of very simple construction yet capable of maintaining a square shape when pressurized.

A further object is to provide a core member having a square shape when pressurized without the necessity of any supporting or reinforcing structure.

In brief, the above and other objects of the invention are achieved by providing a core for use in casting hollow concrete beams or the like including an elongated hollow tubular core member or body formed of an elastomeric material and having a polygonal outer periphery in cross section. The ends of the body are sealed, and means are provided for admitting a pressurizing medium such as air to the interior of the body. In accordance with an important feature of the invention, the body is formed entirely of the elastomeric material and does not include any other supporting or reinforcing structure. Rather, the body is constructed to maintain its polygonal outer shape when pressurized without the necessity for any additional support.

In one embodiment of the invention, the tendency of the body to become round upon pressurization is counteracted by forming an inward bow or concavity into its sides. In another arrangement, the inner surface of the body is circular in cross section while the outer surface is polygonal. Upon pressurization, there is no tendency for the outer shape to become distorted or rounded.

The invention and its objects and advantages may be better understood from the following detailed description wherein reference is made to the accompanying drawing in which:

FIG. 1 is a fragmentary, elevational view, partly in section, of a core embodying features of the present invention;

FIG. 2 is an enlarged, sectional view taken along the line 2-2 of FIG. 1;

FIG. 3 is a fragmentary, elevational, sectional view, on a reduced scale, of part of the core of FIG. 1; and

FIG. 4 is a view similar to FIG. 2 illustrating an alternative embodiment of the present invention.

Referring now to the drawing and initially to FIGS. 1 and 2 there is illustrated a core constructed in accordance with the present invention and designated as a whole by the reference numeral 10. The core 10 is used in a process of casting hollow concrete beams and in general includes a central, hollow core member or body generally designated as 12, the ends of which are sealed by cap members 14 and 16. Cap 14 is provided with a valve assembly 18 of known construction so that a pressurizing medium such as pressurized air can be admitted to and released from the core member 12.

In use, the core 10 is supported within a mold into which concrete is poured in order to cast a beam. The core is surrounded by concrete, and in order to prevent the core member from collapsing under the weight of the concrete, it is pressurized by admitting a pressurizing medium to its interior through the valve assembly 18. The core remains pressurized while the concrete sets, and thereafter the pressure is relieved by opening the valve assembly 18. The core is then pulled from the concrete to reveal a tunnellike opening or passage through the beam.

In accordance with an important aspect of the present invention the core member 12, although extremely simple and therefore inexpensive to construct, is generally square in shape and is capable of retaining its square shape when pressurized. The square shape gives rise to a saving in material cost since less concrete is required as compared with a beam formed around a circular core having a diameter equal to a side of the square. Furthermore, as compared with such a round core the square shape does not substantially detract from the strength of the beam. It should be appreciated that nonround shapes other than square are within the scope of the present invention. Although the advantages of a square core are widely appreciated, the present invention provides a simple core capable of retaining a square shape without the use of complex supporting and reinforcing structure heretofore thought necessary with a pressurized, nonrigid core.

In accordance with one feature of the invention the core member 12 is able to maintain its square shape when pressurized because in its relaxed, unpressurized state the sides of the core member are concave or bowed inwardly. The core member 12 is shown in its relaxed state in FIG. 2 where the inward bow or concavity is indicated by the dimension *a*. The inward bowing of the sides of the core member counteracts the tendency of the core member to become rounded or distorted when subjected to internal pressure. When the core member is pressurized, the wall 12a of the core member is deformed to some extent, but this deformation merely straightens the walls and in fact results in the core member becoming more square rather than less square.

Another aspect of the invention contributing to the ability of the core member 12 to remain in a substantially square shape when pressurized is the choice of material used. In accordance with the invention, the material should be flexible enough so that the body can be deformed slightly when pressurized. However, the material should exhibit the characteristic of stiffness to the extent that the deformation of the sides of the core member is limited so that the sides do not become appreciably convex when the core member is pressurized. Furthermore, the material should be resilient so that when the pressure within the core is relieved the member 12 reverts to its original shape and can be removed from the concrete beam. One material which has been found to be suitable in all these respects and which is also advantageously light in weight is a low density polyethylene. By way of example, and without limiting the scope of the invention, suitable materials are a low density semirigid polyethylene identified as Number 0224 sold by Union Carbide and Carbon Corp., and a material sold under the trademark "Tenite," Number 860, and available from Tennessee Eastman Company.

One important and heretofore unobtainable advantage of the core of the present invention is the simplicity of the core member 12 and the ease with which it can be fabricated. Thus

the core member may be formed of a single, homogeneous material throughout and may have a uniform cross section throughout its length. In addition, the core member may have a wall of uniform thickness throughout. Accordingly the core member may be entirely formed in a simple and inexpensive extrusion operation, although other methods could be used to form the core member.

It will be appreciated that in practical embodiments of the invention, the core member may be of substantial length, and for this reason the core 10 has been illustrated in broken form in FIG. 1. As shown in FIG. 3, where long lengths are required two or more members 12 may be spliced together by means of a sleeve 20 cemented inside the abutting ends. The core may be supplied in a variety of sizes ranging for example from 4 to 12 inches in width and in lengths up to 60 feet or more. The degree of inward bow indicated by the dimension *a* in FIG. 2 may vary with the size of the core member and also with the material used in the core. By way of example, in a core member having a 4-inch width and made of low density polyethylene an inward bow of one thirty-second inch may be used.

Proceeding to a more detailed description of the cap members 14 and 16, the cap 14 includes a body 22 from which extends a pluglike projection 24 snugly received with the end of the core member 12. A pair of recesses 26 and 28 in the cap 14 are separated by a wall 22a and are selectively intercommunicated by the valve assembly 18. A bail or ring 30 is supported on the cap 14 permitting the core 10 to be pulled from a beam after setting of the concrete.

Sealing of the other end of the core member 12 is accomplished by means of the cap member 16 which includes a body 32 and a pluglike projection 34 received within the core member 12. In order securely to seal the end of the member 12, a gasket 36 is expanded against the inner wall of the member 12 by an eye bolt 38 threaded into a compression plate 40.

Referring now to FIG. 4, there is illustrated another embodiment of the present invention. This figure illustrates in cross section a core member embodying important features of

the invention and generally designated as 50. It should be understood that although cap members are not illustrated for the core member 50, they may be similar to the cap members 14 and 16 used with the core member 12 described above.

5 In accordance with a feature of the invention, the core member 50 is simple in shape and is inexpensive to construct but is nevertheless able to retain a square or other nonround outer shape when pressurized, without the necessity for reinforcing or supporting structure. This is accomplished by 10 providing the core member 50 with a generally square outer wall 50a and a circular inner wall 50b. When pressurized, due to the provision of the circular inner wall 50b, there is no tendency for the shape of the square outer wall 50a to become distorted.

15 The core member 50 may also be fabricated inexpensively from a single, homogeneous material in an extrusion process. Any desired elastomeric material such as rubber or the like may be used. Cap members for the core member 50 may be identical to the members 14 and 16 except that their projecting plug portions would be round to fit within the circular inner wall 50b.

20 While the present invention has been described in connection with the details of illustrative embodiments thereof, other embodiments and modifications may be devised by those skilled in the art which fall within the spirit and scope of the invention. The details of the described embodiments should not be taken to limit the invention except insofar as set forth in the following claims.

I claim:

30 1. A core for use in casting hollow concrete beams or the like comprising an elongated hollow tubular body formed of a flexible extruded rubber material, means for sealing the ends of said body, and means for admitting a pressurizing medium to the interior of said body, said body in cross section having a substantially rectangular outer periphery and having a substantially circular inner periphery so that the shape of the outer periphery is maintained upon pressurization of the body.

35 2. The core of claim 1, said outer periphery being square.
